UNITED STATES PATENT OFFICE.

ALEXANDER E. KEITH, JOHN ERICKSON, AND CHARLES J. ERICKSON, OF CHICAGO, ILLINOIS, ASSIGNEES, BY MESNE ASSIGNMENTS, TO AUTOMATIC ELECTRIC COMPANY, A CORPORATION OF ILLINOIS.

AUTOMATIC TELEPHONE EXCHANGE.

Application filed June 18, 1902. Serial No. 112,224.

To all whom it may concern:

Be it known that we, ALEXANDER E. KEITH, JOHN ERICKSON, and CHARLES J. ERICKSON, all citizens of the United States, 5 residing at Chicago, in the county of Cook and State of Illinois, have invented new and useful Automatic Telephone Exchanges, of which the following is a specification.

Our invention relates to automatic telephone exchanges, and our object is to provide a new system of mechanism adapted to use in large exchanges of say ten thousand or more subscribers without introducing undue complication of either the switch mechanism or interconnecting wires. In Letters Patent of the United States for automatic telephone exchanges, granted to us December 5, 1899, and numbered 638,249, in connection with Letters Patent of the United 10 States for calling devices for automatic telephone exchanges granted to us January 11, 1898, and numbered 597,062, is embodied a system of automatic telephone exchange which in practice consists of a combination 15 of the calling device at the subscriber's station and the exchange mechanism at the central station. The calling device consists of a pivotally mounted disk having at one side marginal edge, ten holes numbered consecutively from 1 to 9 and 0, and is operated to 20 call a certain number by inserting a finger in a hole designated by the proper numeral and turning the disk until the finger contacts a stop and is then released, after which, 25 by virtue of a spring the disk is returned to the first position, and this return movement through proper step by step mechanism, causes electric currents alternately 30 over two line wires to operate the proper magnets at the central exchange, and set the subscriber's switch to the contact point wanted, to place him in communication with another subscriber.

In the above described system the selector 45 or subscriber's switch for a system of one hundred subscribers has one hundred contact points, disposed in ten concave rows of ten in each row, and each of these contact points is adapted to be engaged by a switch arm mounted on a shaft which is fitted to move step by step both vertically and in a 50 rotary direction.

In automatic telephone exchanges of the

above described kind, the contact points in the banks of each switch or selector are 55 directly connected by interconnecting or bank wires with the contact points of the banks of all the other switches, and the first electrical impulse is transmitted through one of two line wires by the step by step calling device, 60 which serves to pick out the "ten" on one line wire, and the next impulse the "unit" of a number less than one hundred through the other line wire, the circuits being grounded in both cases when in action. 65

In the new system embodied in the drawings and specification herewith, and which is adapted to exchanges of ten thousand or more subscribers, although the calling devices and the general principles involved in 70 the construction of the switches are similar to those embodied in the invention shown in the patents hereinbefore referred to, yet several important new devices adapted to perform new functions have been added, 75 and the electrical connections of the switches are such that the latter are arranged relatively in several groups of which, in the first group there is one switch for each subscriber, the switches in this group being termed first selectors. The switches in the second group are termed second selectors, and in number are usually not more than 80 ten per cent of the number of switches in the first group.

The switches in the third group are termed connectors, and are usually less in number than the number of switches in the first named group, and may be equal in 85 number to the number of switches in the second named group.

The several groups of both selectors and connectors may each be subdivided into secondary groups or sections as may be desired.

In this new system, the first electrical impulses caused by the calling device, instead of first connecting directly to the subscriber's line, automatically connect the calling subscriber's line to some one of ten or more trunk lines which lead to groups of switch instruments or second selectors, which are in turn connected with another group of switch instruments or connectors, which latter operate to connect with the sought for subscriber so that, in an exchange for one hundred to nine hundred and ninety-nine 100 105

subscribers, the first electrical impulses sent in by the calling device will pick out some one of the trunk lines leading to a group of selector switches numbered for the first digit 5 of the number of subscriber sought, and the next electrical impulses select from this group the contact point representing the last two digits of the subscriber's number sought, but in exchanges of this kind arranged 10 for a still larger number of subscribers than last above mentioned, say for from one to ten thousand subscribers, as is embodied in the present invention, the electrical impulses caused by the calling device, automatically 15 pick out first, the thousand group of second selectors and then, the hundreds group of connectors in which the called number is found.

Since several kinds of calling devices may be 20 used to control electric currents at the proper time, and over the proper line, automatically, and since such constructions and their operation are somewhat intricate, and would unnecessarily complicate this case, we have 25 substituted therefor simple calling keys by which the action of the proper mechanism at the proper time may be fully and easily illustrated.

The automatic calling device particularly adapted 30 to control the electric currents for this new system is the subject of a separate application for patent.

The principal object of our invention is to provide practical means whereby from 35 any of the secondary groups or sections of the subscriber's or first selectors the proper interconnecting of trunk lines leading to any other desired first selector in the same or any other group of first selectors, may be automatically 40 and very quickly selected, and thereby connect any two distant subscribers whose lines are not engaged, the operation of calling another subscriber being such that should several of the trunk lines be in use, the first and second selectors would, so to 45 speak, automatically pass over these busy trunk lines and select the first idle trunk line through which communication could be established, all of which is more fully described hereinafter, and illustrated in the accompanying drawing in which:

Fig. 1, is a front elevation of one of either the first or second selectors, and Fig. 2, is a side elevation of the same looking in the direction indicated by arrow A, Fig. 1.

Fig. 3, is an elevation of the opposite side shown in Fig. 2, but with the parts below the main frame removed.

Fig. 4, is a plan of what is shown in Fig. 3.

Fig. 5, is a cross section on broken lines B, C, Fig. 3, to illustrate the normal position of several of the operative parts.

Fig. 6, is a cross section, same as the outer portion of Fig. 5, to illustrate the main

switch shaft's longitudinal motion detent in engagement, and also the inward position of the detent's trip and locking springs.

Fig. 7, is a cross section on broken lines D, E, Fig. 3, to illustrate normal position 70 of several parts not shown in Fig. 5.

Fig. 8, is the same as a portion of Fig. 7, but with the main switch shaft's rotary detent in the position it is made to assume when the switch shaft's longitudinal motion 75 detent is in the engaged position shown in Fig. 6.

Fig. 9, is the same as Fig. 8, but with the rotary detent in engagement with the first tooth of the main switch shaft's rotary 80 ratchet, and showing the inward or operated position of the arm through which the auxiliary switch is moved to the normal position by virtue of the release armature spring.

Fig. 10, is a cross section on broken line 85 F, G, Fig. 3, showing the auxiliary switch mechanism in the normal position, with several important parts in broken lines.

Fig. 10^A, is a perspective view of the auxiliary switch contact points, as they appear 90 embedded in a bracket of insulating material shown in end elevation in Fig. 10, attached to the side of the main frame.

Fig. 11, is the same section as Fig. 10, but with the parts in the operated position. 95

Figs. 5 to 11, inclusive, except Fig. 10^A, are sections on the broken lines stated, looking in the direction indicated by arrow H, Fig. 3.

Figs. 12, 13, 14 and 15 are partial side elevations of an auxiliary switch release and a cut-out mechanism, to illustrate different 100 positions of the operative parts.

Fig. 16, is a side elevation of one corner portion of what is shown in Fig. 2, but with 105 several parts removed, to illustrate the means for permitting the main switch shaft's ratchet detents to be brought into engagement with ratchet wheel teeth on this switch shaft, by the disengagement of a release lock spring.

Fig. 17, is a side elevation of a detached portion of what is shown in Fig. 16, and 110 illustrates second position from normal of the detent release lock spring.

Figs. 18, 18^A and 18^B, respectively, show a side and front elevation, and a bottom plan 115 of the main switch shaft's combined ratchet detents.

Fig. 19, is a bottom plan of the release-lock spring, shown in end elevation in Figs. 16 and 17.

Figs. 20, 21 and 22, are front elevations of a pair of relay magnets, and the operative mechanism in connection therewith, the same as shown at the top of Fig. 2, but on an enlarged scale, with the operative parts in several different positions, as when in use.

Fig. 23, is an elevation of a pair of re- 130

tardation magnets, same as shown mounted at the rear of the relay magnets in Fig. 2, but on same scale as Fig. 20, the operative parts being in the normal position.

5 Fig. 24, is a side elevation of a portion of the principal operative parts in the normal position, of a connector which is used for all the groups of connectors, and which differs in several minor parts from the 70
10 selectors illustrated in the preceding figures.

Fig. 24, also shows an electromagnet secured at the lower end of the frame, which serves as a means for operating a spring switch, whose parts are normally in the talking 75
15 circuit, but which circuit may be cut out, and the party be placed in the signal circuit.

Fig. 25, is the same as a portion of Fig. 24, but showing several of the parts of the 20
20 connectors in the operated position.

Figs. 26 and 27, are cross sections on broken line I, J, Fig. 24, to illustrate, respectively, the normal and the operated position 25
25 of mechanism adapted to lock, at normal position, the auxiliary switch of the connectors.

Fig. 28, is a detail sketch, to illustrate means for imparting movement to unlock 30
30 the auxiliary switch of the connectors.

Fig. 29, is a plan of a circuit breaker operated by an electric motor, and showing 35
35 diagrammatically the battery connections.

Figs. 30 and 30^A, show, respectively, a side and an end elevation of a three part commutator for a circuit breaker, and Figs. 31 40
40 and 31^A, a side and an end elevation of a piece of tubular insulation serving to insulate the parts shown in Fig. 30, from the shaft of the rotary circuit breaker of Fig. 29.

Fig. 32, is a side-elevation of the commutator of a single circuit breaker, which is shown in position in Fig. 29.

Figs. 33 and 34 are connected diagrammatic illustrations, to indicate the general 45
50 system of electrical connections from one subscriber to another, and the course of the signalling and talking circuit, together with battery connections direct and through the circuit breaker, the induction and retardation coils and the relay magnets, of which illustrations, in Fig. 33, there are three sections indicated by the letters A, B and C, and in Fig. 34, there are four sections, indicated by letters D, E, F and G, of which 55
60 sections A, B and C, of Fig. 33, A shows a telephone receiver, hook, signal magnets and two ordinary signal keys, to represent a subscriber's calling station; while B and C, respectively, represent a first and a second selector.

In these figures the resistances and the retardation coils are shown by their conventional forms but in Fig. 47, circles are used to designate them.

65 In Fig. 34, sections D and E, respectively,

represent a connector and a first selector, through which connection is made to the called subscriber's station at section F, which is a duplication of station A, while section G, is the central station battery and 70
75 connexions, together with devices for delivering electric currents through a series of wires of which latter, four are also seen in Fig. 33, and referred to hereinafter.

Figs. 35 and 36, show, diagrammatically, the system of electrical connections, to illustrate the course of the current in the operation of picking out a trunk line not in use, and why no connection can be made 80
85 with a busy trunk line.

Figs. 37 and 47, illustrate, diagrammatically, a portion of the three groups of first and second selectors, and of a portion of one group of connectors, and the manner of connecting them together and with the source 85
90 of electric current.

Figs. 37 and 47, also illustrate, as herein-after fully described, how, through the action of any subscriber's selector, the trunk lines are automatically selected, the automatic mechanism being capable of passing 90
95 all engaged trunk lines but certain to make connection with the first one not in use.

In Fig. 37, the single curved row of contact points are indicated, together with the main switch shaft, and a switch arm for each selector and connector of what we term the private banks, and also the complete circuits for said banks including the auxiliary switch arms therefor and the main 100
105 battery. In Fig. 47, double curved rows of contact points are indicated, in what we term the connecting banks of contact points, both the private and connecting banks being simply indicated in Figs. 1 and 2, attached to the lower portion of both the 110
115 selectors and connectors. In other words, the two figures are virtually horizontal sections through the shaft and contact making mechanism in two planes, 37 being through the private bank or the bank by means of which connections are made to prevent interference after a talking circuit has been established and 47 through the connecting bank by means of which a talking circuit is established.

The particular construction to prevent cross talk is fully illustrated in Figs. 38 to 45, inclusive, in which Fig. 38 is a plan on a line of separation between the separate strips of insulating plates which 115
120 separate one row of contact points from the others of the connecting bank, the main switch shaft and bank side supporting rods of the frame being shown in cross section, and the contact points of one side of one of the double rows and the outer projecting ends of the closely adjacent row are disposed in proper position in plan view, arranged in pairs, of which, each contact point 125
130 is insulated from all the others and each is

adapted to be contacted by one member of the double main switch arms, which latter are insulated one from the other, and from the main switch shaft; as illustrated in Fig. 39, where is shown a side elevation of a portion of the main switch shaft, with a single contact point knife switch arm insulatingly mounted thereon, and in contact with the usual single contact points of the private banks; and there is also the double switch arm in contact with the double contact points of the connecting banks, the banks both being shown in section, to partially illustrate the comparative difference in arrangement of the private and connecting banks, which latter are illustrated in detail in Figs. 40 to 45, inclusive, in which, Figs. 40 and 41 are, respectively, a plan and a front elevation of a bank of only five rows of double contact points which will serve to fully illustrate the construction of full banks of ten double rows of contact points.

Fig. 42 is a front elevation of one of the sections comprising a row of double contact points in Fig. 41.

Fig. 43 is a front elevation of one condenser plate section, which is disposed between adjacent double rows of contact points, for the purpose of preventing cross talk, as is hereinafter explained.

Fig. 44 is a cross section, on broken line K, L, Fig. 40, to clearly illustrate the component parts of the bank.

Fig. 45 is a perspective view of a metal comb shaped piece for making electrical connection between all the metal condenser plates of the bank, the same being shown in position in Fig. 41 at each side portion of the drawing.

Fig. 46, illustrates, diagrammatically, three connectors, of which, two are in section H, and one in section I, and also illustrates the private bank wires and battery connections, for the purpose of showing the difference between a busy connector or line, a connector at normal, and a third connector seeking to make a connection with a busy line.

Similar numerals indicate like parts throughout the several views, and since in both the selectors and connectors most of the important parts may be, and are, in this instance, substantially alike, they are designated, when alike, by the same numerals, the parts, however, which are not common in the selectors and connectors are hereinafter designated by separate numerals, and the differences, both in construction and function particularly designated; and since many of the principal operative parts of this system are practically the same as shown and described in our United States Patent Number 638,249, hereinbefore mentioned, a minute description of all such parts is not necessary, since this invention does

not consist so much in the particular mechanical movements employed, as in other features hereinbefore referred to, and hereinafter fully described.

The frames 1 of both the selectors and connectors are the same, and there is, in common, a vertically disposed step by step sliding, rotative main switch shaft 2, mounted on the frame, and this shaft is provided with switch arms 3, 4 and 5, which, by virtue of the step by step sliding, rotative motion of the shaft, are adapted to contact any one of two banks 6 and 7 of contact points, which are arranged in concave rows, Fig. 1.

The step by step rotative motion is imparted to the main switch shaft 2 by virtue of electromagnet 8, which operates long ratchet wheel 9 through lever 10 and pawl 11.

The step by step longitudinal movement of shaft 2 is accomplished by the action of vertical electromagnet 12, which operates cylindrical ratchet 13 through vertical magnet lever 14 and pawl 15.

Shaft 2, is successively lifted step by step against gravity, and is rotated against the resiliency of a spring 16 connecting the lower end with the frame, as shown in Figs. 1 and 2, the downward movement of the shaft being limited at its normal position by a collar 17, or any other suitable device contacting the frame, and the normal rotary position is maintained by a pin 18 which contacts a pin 19 projecting from the top of the frame.

A small short pin 20, Figs. 1 and 2, in the top of the frame will be contacted by pin 18 and hold the shaft in the initial position, if an effort is made to rotate it, until after one vertical step movement is completed.

There is a double detent having one arm 21 adapted to engage the circular teeth of the cylindrical ratchet 13, and another arm 22 for engaging the teeth of ratchet wheel 9, the two detents being yieldingly held in engagement with the ratchets by spring 23.

Shaft 2, as in the previous inventions hereinbefore referred to, is provided with means which prevents any further vertical movement after the shaft has been rotated one step, and comprises a stationary detent 24 which is secured to frame 1, Figs. 1, 3, 4, 5 and 6, and the point thereof is in a groove 25, which is longitudinal of cylinder ratchet 13, and plainly shown in Fig. 3, and in cross sections of the ratchet in Figs. 5 and 6.

The point of stationary detent 24 will remain in groove 25 so long as shaft 2 is only moved step by step vertically, but if it is moved but one rotative step, the point of the detent engages in a groove between two teeth of the cylinder ratchet 13, and although it permits the shaft to rotate farther, now prevents any longitudinal or vertical movement either way, thus effectually pre-

venting the switch arms 3, 4 and 5 from being bent or injured, when they are once in engagement with any of the concave rows of contact points of banks 6 and 7 so that, in order to reach any particular row of contact points, a vertical step by step movement must first be made to the particular row wanted, and when the particular contact point is found in the row, the operation of the release must first cause the shaft to reverse its motion in a rotary direction, so that the switch arms 3, 4 and 5 are clear of the contact points, and detent 24 is in groove 25, before shaft 2 falls to the initial position shown in Figs. 1 and 2.

The auxiliary switch, in both the selectors and connectors, in this instance, comprises five switch arms 26, 27, 28, 29 and 30, which are insulatedly secured at one end to an arm 31 secured to shaft 32, which latter is revolutely mounted at the ends in frame 1.

The switch arms 26 to 30, inclusive, are normally in engagement with five insulated contact points 33, 34, 35, 36 and 37, Figs. 1, 3, 10, 10^A and 11, but are adapted by a movement caused by spring 38 on shaft 32 to be disengaged from these points, and be placed in connection with five other insulated contact points 39, 40, 41, 42 and 43.

30 This far, the selectors and connectors are alike, but the five auxiliary switch arms of both the first and second selectors are not held by the same means in engagement with the contacts 33 to 37, inclusive, in the normal position, nor are they caused to be disengaged to engage contacts 39 to 43, inclusive, by the same means as in the connectors, and this constitutes the real difference in the construction between the connectors and selectors, with the exception of the ringing magnet attached to the connector switch, Fig. 24.

In the selectors, the five switch arms are held in engagement in the normal position shown in Figs. 1, 2, 3, and particularly Fig. 10, with the outer row of contact points 33, 34, 35, 36 and 37, by means of an arm 44 which forms a bell crank lever with arm 31, and extends across switch frame 1, and the outer end portion of this arm is adapted to be engaged by a shoulder 45 at the top of a spring arm 46 extending from the armature 47 of a magnet 48, for controlling the auxiliary switch, and may also be engaged by a second shoulder 49 at the top end of a rigid arm 50, which also extends from armature 47.

60 The shoulder 45 of spring arm 46 is disposed at a less distance outwardly than shoulder 49 of arm 50, as is plainly shown in Fig. 2, and especially in Figs. 12 to 15, inclusive, so that the shoulders of these arms do not register for the purpose as is hereinafter fully explained in describing the operation of the auxiliary switch.

In the release mechanism, plainly shown in Figs. 1 to 8, inclusive, of both the selectors and connectors, there is a short arm or crank 32¹ attached to the upper end of shaft 32, and at the outer end of this crank 70 is pivotally secured the end of a bent connecting rod 51 which extends across to the opposite side of the main frame, where its slotted or bifurcated end is in engagement with an arm 52 of the double detent 21.

53 is the release electro-magnet, whose armature 54 is pivotally attached at one end to frame 1, and is held out of contact with the magnet by means of a comparatively strong spring 55.

Firmly attached at one end to the outer end of armature 54 is a release lock spring 56, Figs. 5, 6, 8 and 19, which extends across to the opposite side of the main frame, and at the outer end of this spring is a hole 57 disposed so as to engage with a projection 58 from double detent 21.

Projecting from magnet lever 14, Figs. 24 and 25, is a hook 59 adapted to contact the under side of spring 56 and disengage the spring from the projection 58 of double detent 21, when lever 14 is operated the first time from the normal position.

In the connectors, Figs. 24 and 25, is shown the auxiliary switch magnet 48, but instead of the switch spring 62 and 63 being attached thereto, as in the selector, there is attached a catch spring 70 having a shoulder at the top end similar to hook spring 46, Figs. 2 and 12, of the selectors, and a rigid armature arm 71, having a bent outer end portion which contacts the catch spring as shown.

The connectors, Fig. 24, also differ from the selectors because armature 69 of magnet 48 is always closed in the initial position, whether the armature of rotary magnet 8 is closed or not, and armature 69 is held in the closed position during the time and for the purpose hereinafter explained.

In the connector, Fig. 24, lever 44 is seen in engagement with the shoulder near the outer end of catch spring 70, when the parts are in the normal position.

Also, the connectors differ from the selectors in that each of them is provided with a yielding controller comprising a rod 76 pivotally connected at one end to the rigid armature arm 71, the other end of this rod being connected to the vertical magnet lever 14, which latter connection is yielding, and constructed as follows:

At one side of vertical magnet lever 14 is an outwardly projecting pin 77, which engages in the slotted end of rod 76, Figs. 24, 25 and 28, and at the opposite side of magnet lever 14 from pin 77 is an arm 78, Fig. 28, to which one end of a flat spring 80 is attached, the outer end of the spring being in engagement with the rod 76 in the

outer end of the slot thereof, Figs. 24 and 28, so that the movement of vertical magnet lever 14 is yieldingly imparted to rod 76, armature arm 71 and armature 69 5 through spring 80.

Now, since, if not prevented, the above described connection of armature arm 71 with vertical magnet lever 14 would cause a release of the engagement of arm 44 with 10 the upper end of armature arm 71, every time main switch shaft 2 is lifted one step, it is prevented primarily by a pin 81, Figs. 24, 26 and 27, which projects downwardly from ratchet wheel 9, and is in contact with 15 a projection 82 on cross arm 44 in any vertical position of shaft 2, before it has been rotated one step, and, thereby the auxiliary switch arms 26, 27, 28, 29 and 30, are held in the normal or out position shown in Fig. 20, at all times, when the vertical movements of shaft 2 are being made. If, however, shaft 2, is revolved one step, as seen in Fig. 27, at any of its several vertical positions, on account of the armature arm 25 71 having no connection with the rotary movement mechanism, but only with the vertical movement lever 14, the cross lever 44, which controls the auxiliary switches, is not disturbed, but serves to hold the auxiliary switch arms in the initial position, 30 as in Fig. 10. If, however, after shaft 2 has been revolved one or more steps, then vertical magnet 12 is energized, and if there is no current passing through magnet 35 48, to attract armature 69, the movement of lever 14, through rod 76, causes armature arm 71 to move from the position shown in Fig. 24 to the position shown in Fig. 25, and disengage the outer end of cross lever 40 44 from the hook of spring 70, Fig. 25; and when vertical magnet 12 is de-energized, and vertical lever 14 and armature arm 71 fall back to the initial position, Fig. 24, the end of cross lever 44 will contact spring 45 70 beyond the hook shoulder thereof and by virtue of spring 38 on shaft 32, move out of engagement with the hook, to the position shown in Fig. 27, when the auxiliary switch arms will assume the inward or 50 second position shown in Fig. 11.

If, however, in the connectors, as will be hereinafter explained, an electric current should be passing through magnet 48, armature 69 would be held down as in Fig. 55 24, and, although, vertical lever 14 may have a movement, it will not be transmitted to armature arm 71 for the reason that, spring 80 at the end of rod 76 is not of sufficient strength to overcome the attraction of 60 magnet 48, and the auxiliary switches named will not be changed from the initial position shown in Fig. 10, to the moved position in Fig. 11, until the current is cut out of magnet 48.

65 In both the selectors and connectors,

shown in Figs. 1, 2, 3, 5 and 6, is a short release arm 83, bent at a right angle at the outer end, Figs. 5 and 6, and this bent portion is disposed so as to be in contact with the outer surface of pawl 15 of vertical lever 70 14 to hold the pawl out of engagement with cylindrical ratchet 13, when lever 14 is in the initial position shown in Figs. 2 and 3, and is for the purpose as follows:

First, pawl 15 must be released from 75 ratchet 13 after every step, in order that main switch shaft 2 may be moved not only in a step by step rotary direction, but also be adapted to be released and fall in the direction opposite to that induced by the 80 action of pawl 15, when necessary, and then, it must be understood that vertical magnet lever 14, on account of serving to release cross arm 44, is fitted to have a greater 85 movement than is necessary to move main switch shaft 2 one step, the first part of the movement being adapted to operate rod 76 sufficiently to release cross arm 44 from the hook at the outer end of spring 70, and only 90 a part of the terminal portion of the movement serving to operate pawl 15 so that the release arm 83 permits pawl 15 to engage the teeth of ratchet 13 only at the terminal portion of its movement, and this portion 95 of the movement is limited by an inclined faced stop 84 projecting from the top of frame 1 and against which face the forward end portion of the pawl contacts with a wedge action, which also serves to lock 100 the ratchet or shaft from moving any more than exactly one step.

After main switch shaft 2 has been moved one or more rotary steps, and stationary detent 24 is in engagement with the teeth of ratchet wheel 13, no farther vertical movement of shaft 2 is possible, yet vertical armature arm 14 is adapted by its initial movement to operate rod 76 and lift magnet armature 69 if magnet 48, Fig. 24, 110 is not energized.

In operating this system of telephone exchange it must be particularly understood that the source of electric current for operating the vertical, rotary, release, and auxiliary switch magnets, and for ringing the signal bells, is supplied at the central station, and for the talking circuit is supplied by a local transmitter circuit, not shown, in the usual manner. In order to more fully understand what is shown in the diagrammatic views 33, 34, 35, 36, 37 and 47, we will refer particularly to Figs. 29 to 32, inclusive, in which is shown on a larger scale than in Fig. 34, means for producing an electric current, and for interrupting a portion of such current for operating the rotary magnets 8, of all the selector switches and ringing the signal bells at the subscribers' stations, and which means consists of a battery 65 having, in this instance, an elec- 125 130

tric motor 85 electrically connected therewith.

The shaft of the motor is extended so as to have mounted thereon commutators 86, 87, 88 and 89, of which, each consists, in this instance, of a cylindrically shaped rotative part, of which, 86, 87 and 88 are mounted on insulated metal sleeve 90, and 89 on sleeve 91.

10 In each of the commutators, one half of the peripheral surface consists of electric conducting material connected with the metal sleeves, and the other half is of insulating material, as indicated in Fig. 30.

15 Sleeve brush 92 connects sleeve 90 with wire 106 from the grounded side of battery 65, while brushes 93, 94 and 95, respectively, connect with wires 96, 97 and 98, of which, wires 96 and 97 are in the ringing or signal circuit, and, for this reason, commutators 86 and 87 are, relatively mounted on sleeve 90, so as to alternately make and break the current over the signal wires 96 and 97.

20 25 Brush 95 connects with wire 98, which leads to the secondary of induction coil 99, and thence to main side of battery 65 through wire 100.

25 30 Sleeve brush 101 connects through wire 102 to wire 100, and commutator brush 103 connects to wire 104, which leads to the rotary magnets 8.

35 At 105 is an incandescent lamp serving as a resistance in what we term the private wire 108, from main side of battery, and leading to the auxiliary magnets 48.

40 The auxiliary switch arms of the selectors, such as 26 to 30, inclusive, Figs. 3, 33 and 34, are permanently connected as follows:

45 Switch arm 26 to relay 75 and rotary line wire 109; 27 to relay 74 and vertical line wire 110; 28 to wire 106 of grounded side of battery 65; 29 to private switch wiper 3 of bank 6 and arm 30 to wire 100 of main side of battery 65.

50 In the initial position in both the selectors and connectors these auxiliary switch arms are engaged with contact points 33, 34, 35, 36 and 37, of which, contact point 33 of the first selector, section B, Fig. 33, is connected to wire 100 of main side of battery through one retardation magnet 73 by wire 111, which wire is also connected to a normal wire 157 of the calling subscriber; contact point 34 is connected to wire 100 of main side of battery by wire 113, through another retardation coil 72 and wire 113 is also connected with normal wire 156 of the calling subscriber; contact point 35 is connected to the middle spring 112, between relays 74 and 75; contact 36 to the auxiliary switch electromagnet 48; and 37 is connected to the vertical motor magnet 12.

55 60 65 After the auxiliary switch has been operated from the initial position shown in

Fig. 10, to that shown in Fig. 11, the switch arms 26 to 30 are in connection with contact points 39 to 43 as follows:

65 Contact point 39 is connected to rotary switch arm 5 of bank 7, Fig. 1, and contact 40 with vertical switch arm 4 of bank 7; 41 has no connection or is a blank; 42 with grounded side of battery 65 through wire 106, and contact 43 has no connection.

70 75 The connections of the auxiliary switch arms and contact points thereof of the second selector switch, Fig. 33, section C, are the same as is shown in section B, with the exception of the normal wires 156 and 157.

80 85 The connections of the auxiliary switch arms and contacts thereof of the selectors, having been indicated, as above, we will now indicate the connections of the auxiliary switch arms of the connectors and contacts thereof which are identical in mechanical construction with the selectors, but differ only in the electrical connections.

90 In the connectors, see Fig. 34, switch arm 26 is connected to relay 75 and interconnecting wire 116; 27 to relay 74 and interconnecting wire 117; 28 to the middle spring 112 of relay 74 and 75; 29 to private switch wiper 3 of bank 6, and arm 30 to wire 100 from main side of battery 65.

95 The auxiliary switch arms of the connectors are connected in the initial position, Fig. 10, as in the selectors, with contact 33, 34, 35, 36 and 37.

100 105 Contact point 33 of the connectors is connected to wire 107 through a resistance 118 and then to the primary side of an induction coil 99, while contact 34 is connected to wire 100 from the main side of battery 65 through resistance 119, only; 35 connects to wire 106 from the grounded side of battery 65; 36 to the auxiliary switch controlling magnet 48; and contact 37 to the rotary motor magnet 8.

110 115 After the auxiliary switch of the connector has been operated to the moved position shown in Fig. 11, the switch arms 26 to 30 are in connection with contacts 39 to 43, and contact 39 connects with battery 65 and wire 100 through one retardation coil 73, while contact 40 connects to wire 100 through another retardation coil 72; 41 connects to wire 106 through a special coil 120, termed the ringing relay coil, which is for the purpose of throwing an alternating current out on a subscriber's line as a call signal; while contact point 42 connects to wire 106 from grounded side of battery and contact 43 is blank or has no connection.

120 125 In the initial position of the mechanism of both the selectors and connectors, the auxiliary switch arms 26 to 30 are engaged with contact points which are in electrical connection with the circuits which operate the vertical magnet 12, the rotary magnet 8, the auxiliary switch magnet 48 and in the

first selectors the contacts 33 and 34 also make connection with two wires 114 and 115, termed the normal or individual interconnecting wires of the called subscriber, 5 as shown in Figs. 33 and 34.

In describing the operation of the first selectors, illustrated in Figs. 1 to 19, inclusive, from the normal position, for convenience of description, we term magnets 8, 12 10 and 53, respectively, the rotary, vertical and release magnets, since they serve to move shaft 2 in a rotary and vertical direction, and to release the same, so that it may return by the action of gravity and spring 16, 15 to the initial position.

In setting the main switch arms 3, 4 and 5, to any particular contact points in banks 6 and 7 from the initial position shown in Figs. 1 and 2, vertical magnet 12 is first 20 energized, when main switch shaft 2 with main switch arms 3, 4 and 5 are lifted by pawl 15 through the pitch of one of the teeth of cylinder ratchet 13, when, although pin 18 at the top of shaft 2 will still be held 25 against pin 19, by virtue of spring 16, at the lower end of the shaft, the latter will be lifted above the short pin 20, Fig. 16, so that the shaft may be rotated step by step 30 in one direction.

During the time shaft 2 is being lifted one step, several other important moves have been made, the first of which is that the end of release lock spring 56 has been lifted 35 clear of projection 58 of double detent 21, 22, Fig. 16, by the action of hook 59 of vertical magnet lever 14, when under pressure of detent spring 23, the release detents 21 and 22 are together brought into engagement with ratchets 9 and 13 of shaft 2, as 40 seen in Fig. 8, then as soon as vertical magnet 12 is de-energized, magnet lever 14 falls back to the initial position, when the release lock spring 56 rests upon the end of projection 58 of double detent 21-22 as seen 45 in Fig. 17.

The parts of the selector or connector are now in such a position that the main switch arms 3, 4 and 5 will be in register with the first or lower rows of contact points of banks 50 6 and 7, and the other parts of the switch not be changed in position if it should be necessary to lift shaft 2, step by step, so that the main switch arms 3, 4 and 5, thereof 55 register with some higher row of contact points, this may be accomplished by successively electrically energizing and de-energizing vertical magnet 12.

When the desired concave row of contact points has been found, the first contact 60 points in the rows will be engaged by the switch arms of shaft 2, by energizing rotary electromagnet 8 once, during which time pawl 11 of lever 10 engages ratchet 9, which is turned the pitch of one tooth and is held 65 by detent 22 in such moved position as shown

in Fig. 9. In the meantime, the outer end of an arm 60 connected with the armature of rotary magnet 8, contacts the armature 47 of magnet 48, which is moved from the open or normal position shown in Figs. 2, 10 and 12, to the closed position shown in Figs. 11 and 13.

Normally, in the selectors, the outer end of arm 44 is held, as shown in Figs. 2, 10 and 12, against shoulder 45 at the top of 70 spring arm 46 of armature 47, but when this armature is depressed to the closed position the stiff arm 50 is moved from back stop pin 61 to the position shown in Fig. 13, when arm 44, now being movable laterally, slides off of 80 shoulder 45 of spring arm 46, and under pressure of spring 38 on shaft 32 the arm moves outwardly to shoulder 49 of stiff arm 50, and if there should be no current through magnet 48 to hold armature 47 in contact, 85 and thereby close the circuit through rotary magnet 8, the arm 50 would fall back to pin 61, Fig. 14, when the cross arm 44, would move out to the position shown in Fig. 15, and the arms 26 to 30, inclusive, of the 90 auxiliary switch, move from outer contacts 33 to 37, inclusive, to inner contacts 39 to 43, inclusive.

Whenever the armature of rotary magnet 8 is operated, the action of the arm 60 connected thereto serves to close armature 47 of magnet 48, and by pressure of insulated pin 64 cause insulated switch springs 62 and 63, Fig. 13, to contact at their top ends and close a circuit, so that a current, if there be 100 any, would pass through these springs.

In calling a distant subscriber by this system, if the first contact point in some particular row of the first selector is not engaged or busy, the action of the rotary 105 magnet 8 would be as follows:

When rotary magnet 8 is de-energized, and armature 47 is permitted to lift by removal of the contact of arm 60 through the resiliency of switch springs 62 and 63 acting 110 on arm 50, the latter falls back to stop pin 61, and releasing itself from arm 44, which at the instant of the release appears as in Fig. 14, the pressure of spring 38 on shaft 32 causes arm 44 to be instantly moved to 115 the position shown in Fig. 15, or as more plainly shown in Fig. 11, where the switch arm 30 is shown connected to contact point 43 of the inner row, instead of the outer row, as shown in the initial position in Fig. 10. 120 If, however, the first contact points in the desired row be engaged or busy the action of the rotary magnet 8 and the private magnet 48 is as follows:

When main switch arm 3, engages the 125 first contact point in the desired row of bank 6, Fig. 1, or more clearly shown in section B, Fig. 35, magnet 48 is energized by current from battery 65 through wire 106, main switch arm 66 of bank 67, intercon- 130

necting wire to arm 3 of bank 6, thence to magnet 48 and by wire 100 to battery and so long as magnet 48 is energized, the springs 62 and 63 of private magnet 48 are held in contact, and close the circuit through rotary magnet 8, battery 65 and commutator 89, and at each revolution of commutator 89 the local circuit from battery 65, of which it forms a part, is opened and closed, and at each closing of the circuit, rotary magnet 8 is energized and in the opening of the circuit is de-energized, causing main switch arm 3 to move, step by step, until it engages a vacant contact point, when magnet 48 is de-energized, causing springs 62 and 63 to separate and open the local circuit through rotary magnet 8.

As the arms 4 and 5 which are seeking to make a talking circuit are connected to the shaft 2 and move in unison with the arm 3 it is evident that as soon as arm 3 has made a contact with an open or "not-busy" line arms 4 and 5 will also have made connection with a contact point through which the talking circuit is established.

Fig. 36, section B, is a duplicate of Fig. 35, section B, except that main switch arm 3 is in engagement with the second contact point of an interconnecting line which is also busy, and Fig. 37, section B, shows the first selector main switch arm 3 in engagement with the third contact point connected with an interconnecting line not busy.

The action of main switch shaft 2 of the second selector to find the proper contact point is the same as described for the first selector.

As stated hereinbefore, the operative parts of the connectors are the same as in the first and second selectors, with the exception that, the mechanism controlling armature 47 of private magnet 48 is adapted to normally hold the armature closed, as is seen in Fig. 24, by the action of spring 70 against armature arm 71, and the step by step rotary movement of shaft 2 in the connector is made by means of the calling key, or other mechanism at the calling subscriber's telephone or station until the desired contact point in the row is found, without any further change in the position of the parts of the switch, which is now set to some particular subscriber's number, and serves as a medium of telephonic communication, as is hereinafter described.

After communication is ended, the operation of release or the returning of the main switch arms 3, 4 and 5, and the other parts, back to the initial position, is accomplished by energizing release magnet 53, when the armature release lock spring 56 is moved from the position shown in Fig. 8, to the position shown in Fig. 6, by the closing of armature 54, when the hole 57 in the end of spring 56 will be engaged by the projection

58 of double detent 21-22, as shown in Fig. 6.

If now release magnet 53 is de-energized, the strong release spring 55 will draw the armature to the open or initial position, and with it the release lock spring 56, and double pawls 21-22 which are thus disengaged from their ratchets and leaves shaft 2 free so that it will first revolve by the action of spring 16 back to the position when the stationary detent is in groove 25 of ratchet 13, and stop pin 18 against pin 19, when it will drop by gravity to the initial position, as in Figs. 1, 2 and 3. In the meantime, on account of the cross rod 51, Figs. 7, 8 and 9, having one end in contact with the arm 52 of double detent 21-22, the disengaging movement of the double detent when cross arm rod 51 is in the position shown in Fig. 9, will cause arm 52 of the double detent, through cross rod 51, and short arm 32¹, to partially revolve shaft 32 against the tension of spring 38, and move the switch arms attached to arm 31 from the inner position shown in Fig. 11, to the outer or initial position shown in Fig. 10.

During the last described movement of shaft 32, arm 44 will be moved from the position shown in Figs. 11 and 15, to the initial position shown in Figs. 1, 10 and 12, the outer end of this arm first moving arm 46 to one side from the position shown in Fig. 15, to that shown in Fig. 14, and then, finally, to the position shown in Fig. 12, when the spring arm shoulder 45 serves as a catch to hold arm 44 in the initial position, and all the power for accomplishing the release, as described, arises from the resiliency of spring 55, after being bent by the action of release magnet 53.

At the top end of all the selectors and connectors in this instance, are four single spool magnets, arranged in pairs as seen in Figs. 1, 2, 3 and 4, and each of these magnets is provided with a separate armature, and to each of which is connected an arm for operating a spring switch, the same, together with their switches, being shown on a large scale in Figs. 20 to 23, inclusive.

Two of the magnets, 72 and 73, Fig. 4, serve also as retardation coils.

Two of the magnets 74 and 75 are wound to serve as relays whose coils are in communication with the subscribers but whose armatures are adapted to operate a switch for supplying electric current from a source local at the central exchange, for operating all the motor magnets.

When current is sent through the vertical line wire 110 from a subscriber's station, relay magnets 74 in both the selectors and connectors operate to close the central station local circuit between spring 137 and center spring 112, Fig. 20, and the retardation magnets 72, Fig. 23, operate to close

the spring 135 and 139, and thereby shunt out a portion of their own resistance; see Fig. 33; and when current is sent through rotary line 109, relay magnets 75 operate to close the local circuit between springs 138 and 112, Fig. 20, and the retardation magnets 73, Fig. 23, operate to close the springs 136 and 139, and thereby shunt out a portion of their resistance.

Referring to Figs. 33 and 34, it must be understood that the auxiliary switch arms 26 to 30, inclusive, are shown as set to the second or moved position, in the first and second selectors, represented in sections B and C of Fig. 33, and also as represented in the connector in section D, Fig. 34.

The first selector indicated in section E, of Fig. 34, is the individual selector of the subscriber at station 3333, indicated in section F, of Fig. 34, and this selector only has the auxiliary switch arms shown in the normal or first position in solid lines, and which is the only position of these arms through which a subscriber may be called, therefore, in describing the course of the current in making connection between the subscriber's station number 3331 at section A, Fig. 33, and the subscriber's station number 3333 at section F, Fig. 34, we will imagine the auxiliary switch arms from 26 to 30, inclusive, being in the first or unmoved position, as indicated, by the broken lines in sections B, C and D, in Figs. 33 and 34.

In calling subscriber number 3333 at section F, Fig. 34, from subscriber's station number 3331 at section A, Fig. 33, the signal key 131 is depressed three times, which makes connection three times between ground 129 and wire 110, when at each depression current flows through line wire 110 and relay magnet 74 of the first selector, section B, Fig. 33, wire 153, then through auxiliary switch arm 27, contact point 34, wire 113, retardation magnet 72, wire 100, battery 65 and ground 106, and thereby energizing relay magnet 74 and closing the local circuit by contacting springs 137 and 112, when local circuit current flows through vertical magnet 12, contact point 37, auxiliary switch arm 30, wire 100, battery 65, ground wire 106, auxiliary switch arm 28, contact point 35, and spring 112, and each time vertical magnet 12 is energized, main switch shaft 2 is moved up one step, and held in such moved position by the engagement of detent 21 with cylinder ratchet 13, the main switch arms 3, 4 and 5 being thus carried up three steps, when they are in position, by virtue of a step by step rotary movement, to engage a row of contact points in the third concave rows of the banks 6 and 7, Fig. 1, which are adapted to connect with a group of second selectors designated by the number 3000.

Now, the second signal key 130 at substation 3331, section A, Fig. 33, is depressed one time, which makes connection between wire 109 and ground wire 129, when at each depression current flows through wire 109 to relay magnet 75 of first selector, section B, Fig. 33, then wire 154, auxiliary switch 26, contact point 33, wire 111, retardation magnet 73, wire 100, battery 65, ground 106, thereby operating relay magnet 75 and closing the local battery circuit through contact spring 112 and 138, when local current flows through wire 155, rotary magnet 8, wire 104, then in section G, commutator brush 103, commutator 89, brush 101, wires 102 and 100, battery 65, ground wire 106, then in section B, Fig. 33, auxiliary switch arm 28, contact point 35, spring 112, thereby energizing rotary magnet 8, and rotating main switch shaft 2 one step, which is held in the rotated position by detent 22, engaging long ratchet wheel 9.

In the meantime, while armature 10 of magnet 8, is in the operated or closed position, it serves to hold down armature 47 of auxiliary switch magnet 48 by means of the attached arm 60, as seen in Fig. 11, and causes auxiliary switch cross arm 44 to assume the position shown in Fig. 13, where it is disengaged from the shoulder 45 of spring 46, and is now held by the shoulder of the hook 49 of armature arm 50.

When rotary magnet 8 is de-energized, the armature thereof in lifting releases arm 60 from contact with armature 47, when the latter assumes the position shown in Fig. 14, when cross arm 44 is released from shoulder or hook 49 of arm 50, and by virtue of spring 38 assumes the position shown in Fig. 15, and the auxiliary switch arms 26 to 30, inclusive, are moved from the normal position shown in Fig. 10, to the second position shown in Fig. 11, and thereby place the first selector, section B, Fig. 33, in electrical communication with the second selector, section C, Fig. 33, through the interconnecting or trunk lines 141 and 142, after which, signal key 131, section A, Fig. 33, is depressed three times, then signal key 130 is depressed once, when electric current flows through the circuits of the second selector, section C, Fig. 33, and the same kind of mechanism is operated in the same manner as described for the first selector, which places the second selector, section C, Fig. 33, in electrical connection with the connector, section D, Fig. 34, through the interconnecting or trunk lines 116 and 117.

The subscriber in calling 3333 has, this far, selected the first interconnecting or trunk line connecting him to a second selector of the group number 3000, and has also selected the first interconnecting or trunk line connecting him to connector numbered 3300.

In operating the connector, section D, Fig. 34, key 131, is depressed three times, which makes connection between wires 110 and ground 129, when at each depression current passes through the relays of the first and second selectors, as hereinbefore described, to relay magnet 74 of the connector, section D, Fig. 34, and closes the local circuit through springs 112 and 137, when local current passes through wire 143, vertical magnet 12, wires 144 and 100, battery 65, ground wire 106, wire 145, contact point 35, auxiliary switch arm 28, wire 146, spring 112, when main shaft 2 is lifted three steps, and held by detent 21.

Then the other key 130 is depressed three times, making connection with wire 109 and ground 129, when at each depression current passes through the first and second selector relays as hereinbefore described, to relay magnet 75, of the connector, section D, Fig. 34, and closes the local circuit through springs 138 and 112, when the local current passes through wire 147, rotary magnet 8, contact point 37, auxiliary switch arm 30, wire 100, battery 65, ground wire 106, wire 145, contact point 35, auxiliary switch arm 28, wire 146, to the beginning at spring 112, when the main switch shaft 2 has been rotated three steps and held by detent 22.

Key 131 is now depressed one time, making connection between wire 110 and ground wire 129, when at each depression current passes through line wire 110 and the first and second selector relays, then, by trunk line 117 to relay magnet 74 of the connector, section D, Fig. 34, thereby closing the local circuit through springs 112 and 137, when local current passes through wire 143, vertical magnet 12, wires 144 and 100, battery 65, ground wire 106, wire 145, contact point 35, auxiliary switch arm 28, wire 146, and spring 112, thereby energizing vertical magnet 12, when vertical magnet lever 14 is lifted, together with connecting rod 76, Fig. 25, and armature arm 71; when cross arm 44, is released from the shoulder of spring 70, and is placed in engagement with the shoulder of arm 71.

If now vertical magnet 12 is de-energized the magnet lever 14 and armature arm 71 return to the initial position, Fig. 24, and cause the release of cross arm 44 from the shoulder of armature arm 71, and also the movement of auxiliary switch arms 26 to 30, inclusive, from engagement with contact points 33 to 37, inclusive, Fig. 10, into engagement with contact points 39 to 43, inclusive, Fig. 11, when the calling subscriber number 3331 is connected, or in the position to talk or signal the called subscriber number 3333.

If, however, this particular line 3333 should be busy, when vertical magnet 12 of

the connector switch is energized, its armature arm 14 would be lifted, but on account of rod 76 being connected to arm 14 through a spring 80, Figs. 25 and 28, as before stated, and the magnet 48 being energized by being in circuit of an electric current, its armature would be held down, as in Fig. 24, and there would be no release of cross arm 44, or change in the initial position of the auxiliary switch arms, and consequently the connection of the busy line would not be interrupted, and thereby secrecy or non-interference would be secured.

The reason why auxiliary switch magnet 48 would be energized when line 3333 is busy, is clearly shown in Fig. 46, in section H, where main switch arm 3 is shown in connection with the third contact 152, in a row of ten contact points and auxiliary switch arm 29 in connection with contact point 42; but, in section I, main switch arm 3 is shown in connection with the third contact 151, in a row of ten, and auxiliary switch arm 29, in connection with contact point 36, the auxiliary switch magnet 48 being energized by current from battery 65 through wires 100 and 108, then magnet 48, in section I, contact point 36, auxiliary switch arm 29, main switch arm 3 to the third contact point 151, then wire 148, contact point 152, section H, then main switch arm 3, auxiliary switch arm 29, contact point 42, and wire 106 to battery 65.

After sub-station at telephone 3331, section A, Fig. 33, is placed in communication with sub-station at telephone 3333, section F, Fig. 34, the subscriber at telephone 3331 presses key 131 one time, breaking connection from wire 133, and closing a circuit from ground 129 to key 131, wire 110, first selector, section B, relay magnet 74, wire 153, auxiliary switch arm 27, contact point 40, main switch arm 4, trunk wire 141, relay magnet 74 of second selector, section C, wire 153, auxiliary switch arm 27, contact point 40, main switch arm 4, trunk line 117, relay magnet 74 of connector, section D, Fig. 34, wire 153, auxiliary switch arm 27, contact point 40, retardation coil 72, wire 100, battery 65, ground 106; closing relay magnet springs 112 and 137, when local current flows through spring 137, wire 143, vertical magnet 12, wire 144, wire 100, battery 65, wire 106, ringing magnet 120, wire 166, contact point 41, auxiliary switch arm 28, wire 146, relay spring 112, energizing ringing magnet 120, also vertical magnet 12, but, as the vertical magnet 12 has very low resistance, and the ringing magnet 120 a very high resistance, the vertical magnet 12 will not be energized sufficiently to operate its armature, but ringing magnet 121 will operate to open the circuit between contact point 163 and spring 161, and close the springs

161 and 162 to contact points 164 and 165, which are in circuit with the signalling commutators 86 and 87, section G, Fig. 34.

The signalling or ringing current flows 5 from commutator 86, section G, of Fig. 34, brush 93, wire 96 to contact point 165 of the connectors, section D, Fig. 34, then spring 162, wires 160 and 111, to main switch arm 5, and wire 114, section E, Fig. 34, then contact point 33, auxiliary switch arm 26, relay magnet 75, to wire 122, section F, Fig. 34, key 124, wire 126, signal bell magnets 174, contact point 173, telephone hook 171, wire 125, key 123, wire 121 and through relay 15 magnet 74 of section E, Fig. 34, auxiliary switch arm 27, contact point 34, wire 115, main switch arm 4 of connector, section D, Fig. 34, wires 113 and 159, spring 161, contact point 164 to wire 97 of section G, to 20 commutator brush 94 and commutator 87, causing the signal bells to ring at sub-station No. 3333.

Referring to Figs. 33, 34 and 47, we will now indicate the course of the talking circuit:

Telephone 3331 in Fig. 33, is shown removed from the hook 167, and we will imagine that telephone No. 3333, in Fig. 34, is removed from hook 171, section F, Fig. 34, 25 when the talking circuit is as follows: telephone 3331, wire 133, key 131, wire 110, first selector relay 74, section B, wire 153, auxiliary switch arm 27, contact point 40, main switch arm 4, trunk wire 141, second selector relay 74, section C, Fig. 33, wire 153, auxiliary switch arm 27, contact point 40, 30 main switch arm 4, trunk wire 117, connector relay 74, section D, Fig. 34, wire 153, auxiliary switch arm 27, contact point 40, wire 118, main switch arm 4, normal wire 115, first selector, Fig. 34, section E, contact point 34, auxiliary switch arm 27, relay magnet 74, wire 121, signal key 123, wire 125, telephone hook 171 (which we will suppose has lifted, after the removal of the telephone), then contact point 172, telephone 3333, wire 126, signal key 124, wire 122, relay magnet 75 of selector switch section E, Fig. 34, then auxiliary switch arm 26, contact 45 point 33, normal wire 114, then main switch arm 5, of connector, section D, Fig. 34, wire 111, contact point 39, auxiliary switch arm 26, wire 154, relay magnet 75, trunk wire 116, to main switch arm 5 of second selector, 50 section C, Fig. 33, contact point 39, auxiliary switch arm 26, wire 154, relay magnet 75, trunk wire 142, main switch arm 5 of first selector, section B, Fig. 33, then contact point 39, auxiliary switch arm 26, wire 154, 55 relay magnet 75, wire 109, signal key 130, wire 132, telephone hook 167, contact point 168, telephone 3331.

It will be noticed by reference to the connector, section D, Fig. 34, that the two con-

tact points 39 and 40 of the auxiliary switch 65 are connected permanently to the main side of battery wire 100 through retardation coils 72 and 73, which is for the purpose of preventing short circuiting voice currents and also for enabling the calling subscriber to 70 operate his releasing mechanism through the selectors and connectors at any time.

The selector indicated in section E, Fig. 34, being in the initial position, the contact points 33 and 34 of the auxiliary switch are 75 shown in connection with main side battery wire 100 through retardation coils 72 and 73 of this selector.

After conversation is ended the subscriber at telephone 3331 releases, or causes the 80 selectors and connectors to return to the initial position by simultaneously pressing both signal keys 130 and 131 once, and thereby simultaneously breaking connection from wires 132 and 133, and making connection with ground wire 129 and causing an electrical impulse through main line wires 109 and 110, relay magnets 74 and 75 of first selector, section B, Fig. 33; then trunk lines 141 and 142, and relay magnets 74 and 90 75 of second selector, section C, Fig. 33, then trunk lines 116 and 117, relays 74 and 75 of connector, section D, Fig. 34, retardation coils 72 and 73, wire 100, battery 65, ground 95 106, and energizing all the above mentioned 100 relay magnets and closing the local release circuits of the first and second selectors in sections B and C, Fig. 33, and connector section D, Fig. 34, through their respective springs 127 and 134, as indicated in Fig. 21, 105 when the local circuit currents flow through springs 127, release magnets 53, wire 100, battery 65, wire 106 and spring 134 to spring 127, when the operated parts of both the 110 selectors and connectors will be released or brought to the initial position in the manner as hereinbefore stated in describing the release mechanism.

When a series of main switch arm contact points 167 or 168, as in bank 7, Figs. 1, 2, are placed in close proximity, in order to reduce the size of the switching mechanism to a small size, and these contact points serve as a connection in the talking circuit of a telephone system, they develop condenser action so that, the objectionable feature of a conversation on one line being transmitted to other adjacent lines is the result.

In order to prevent this, so called, cross talk we have provided the construction for the connecting bank 7 which is plainly shown in Figs. 38 to 45, inclusive, and consists, in this instance, Figs. 41 and 44, of condenser plates 169 between the double rows of contact points 167 and 168, the rows of contact points being insulated, one from the other, and from the condenser plates by layers of insulating material 171.

5 The condenser plates 169 are interconnected, in this instance, by means of strips of metal 170 fashioned in the form of a comb, whose teeth 172 each contact a condenser plate, and the ends of the connecting plate are connected with the end plates 173 and 174 of the banks, so that, the 10 tendency of induction-currents in adjacent contacts is neutralized and all cross talk prevented.

10 We claim as our invention:

1. In a telephone exchange having a series of circuits leading from subscribers' stations, a series of selectors, one for each station, an automatically operated progressively movable switching mechanism including an auxiliary switch for placing the selectors in electrical connection, and a yielding controller for said auxiliary switch.
- 15 2. In a telephone exchange having a series of circuits leading from subscribers' stations, a series of selectors, one for each station, an automatically operated progressively movable switching mechanism including an auxiliary switch for selecting the connection between the selectors, and a yielding controller for said auxiliary switch.
- 20 3. In a telephone exchange having a series of circuits leading from subscribers' stations, a series of first selectors, one for each station, a second series of selectors, an automatic progressively movable switching mechanism including an auxiliary switch, and a yielding controller for said auxiliary switch, said mechanism for placing every first selector in electrical connection with every other first selector.
- 25 4. In a telephone exchange having a series of circuits leading from subscribers' stations, a series of selectors, one for each station, and a number of lines adapted to electrically interconnect the selectors, trunk hunting switches for selecting one of said lines, an automatically operated progressively movable switching mechanism including an auxiliary switch for completing the connection, and a yielding controller for said auxiliary switch.
- 30 5. In a telephone exchange having a series of circuits leading from subscribers' stations, a series of selectors, one for each station, and a number of lines adapted to electrically interconnect the selectors, trunk hunting switches for selecting the first idle 35 one of said lines, an automatically operated progressively movable switching mechanism, including an auxiliary switch for completing the connection, and a yielding controller for said auxiliary switch.
- 40 6. In a telephone exchange having a series of circuits leading from subscribers' stations, a series of selectors, one for each station, and a number of lines adapted to electrically interconnect the selectors, trunk hunting switches operating to pass by a busy

line and to select the first idle one of said lines, an automatically operated progressively movable switch mechanism including an auxiliary switch for completing the connection, and a yielding controller for said auxiliary switch.

7. In a telephone exchange having a series of circuits leading from subscribers' stations, a series of selectors, one for each station, and a number of lines adapted to electrically interconnect the selectors, trunk hunting switches for selecting one of said lines, an automatically operated progressively movable switching mechanism for completing the connection, comprising an electromagnet, 70 a source of electrical current therefor, a circuit breaker, a switch for controlling said circuit breaker, and yielding means for operating the switch, substantially as stated.

8. The combination in a telephone exchange having a series of subscribers' lines leading therein, and such lines having insulated terminals arranged in rows and adapted to being electrically connected with, 80 of a body of metal between the rows, for 90 the purpose stated.

9. The combination in an automatic telephone exchange having a series of subscribers' lines leading therein and having a system of interconnecting switches of which 95 latter each is provided with rows of separately insulated contact points each adapted to be contacted by arms which complete the interconnecting circuit, of a body of metal disposed between each of the said 100 rows for the purpose stated.

10. The combination in a telephone exchange having a series of subscribers' lines leading therein which have insulated terminals arranged in a plurality of rows and 105 adapted to being electrically connected with, of a body of metal between the rows and a plurality of such bodies in electrical communication for the purpose stated.

11. The combination in a telephone exchange having a series of subscribers' lines leading therein, of insulated terminals in the lines arranged in pairs each adapted to being electrically connected with any other pair, the pairs of terminals arranged in rows 115 and a body of metal disposed between the rows for the purpose stated.

12. The combination in a telephone exchange having a series of subscribers' lines leading therein, of insulated terminals in 120 the lines arranged in pairs each adapted to being electrically connected with any other pair, the pairs of terminals arranged in a plurality of rows, a body of metal between 125 the rows and a plurality of such bodies in electrical connection.

13. In a telephone exchange, a main switch and an auxiliary switch, an electromagnet for each, and means for mechanically closing the armature of the auxiliary 130

switch magnet and simultaneously closing the circuit through said auxiliary magnet.

14. In a telephone exchange, a main switch and an auxiliary switch, an electro-magnet for each, means connected with the armature of the auxiliary switch magnet for holding the switch in one position and means on the armature of the other magnet for mechanically closing the auxiliary switch magnet armature and simultaneously closing the circuit through said auxiliary switch magnet.

15. In a telephone exchange, a main switch and an auxiliary switch, an electro-magnet for each, flexible terminals adjacent to the auxiliary switch magnet, means on the armature of said auxiliary switch magnet for closing said terminals, means on the armature of the other magnet for mechanically closing the armature of the auxiliary switch magnet, and means for simultaneously passing a current through each of said magnets.

16. In a telephone exchange having a series of circuits leading from subscribers' stations, a series of selectors, one for each station, a second series of selectors and a series of connectors, a plurality of circuits for interconnecting the selectors and connectors, each circuit including an electro-magnet, the armature of the magnet of one of said circuits being normally closed and the other ones being open, and a switch for controlling said circuits.

17. In a telephone exchange having a series of circuits leading from subscribers' stations, a series of selectors, one for each circuit, a second series of selectors and a series of connectors, a plurality of circuits for interconnecting the selectors and connectors, each circuit including an electro-magnet, the armature of the magnet of one of said circuits being normally closed and the other ones being open, positive means for closing the open armatures and yielding means for opening the closed armature, and a switch for controlling said circuits.

18. In a telephone exchange having a series of circuits leading from subscribers' stations, a series of selectors, one for each circuit, a second series of selectors and a series of connectors, a plurality of circuits for interconnecting the selectors and the connectors, each circuit being provided with an electro-magnet, the armatures of which normally stand open except one in each connector which is normally closed, and yielding means for moving the closed armature.

19. In a telephone exchange having a series of circuits leading from subscribers' stations, a series of selectors, one for each station, a second series of selectors and a series of connectors, a plurality of circuits for interconnecting the selectors and the connectors, each circuit including an electro-

magnet, the armature of one of the magnets of each connector being normally closed and the others are open, a switching mechanism in each selector and connector for controlling said circuits, locks for holding the switching mechanisms in their normal position, releasing means for the locks, the releasing means for the lock in the closed armature circuit being yielding.

20. In a telephone exchange having a series of circuits leading from subscribers' stations, a series of selectors, one for each station, a second series of selectors and a series of connectors, a plurality of circuits for interconnecting the selectors and the connectors, one of which is provided with an electro-magnet and a normally closed armature, a switching mechanism in each selector and connector for controlling the circuits and provided with an arm, shouldered mechanism for engaging with said arm and holding the switching mechanism in its normal position, and yielding mechanism for operating the closed armature.

21. In a telephone exchange having a series of circuits leading from subscribers' stations, a series of selectors, one for each station, a second series of selectors and a series of connectors, a plurality of circuits for interconnecting said selectors and connectors, one of which is provided with an electro-magnet whose armature is normally closed, a switching mechanism in each selector and connector for controlling said circuits and provided with an arm, two shouldered members for engaging with said arm and holding it in its normal position, said shoulders being out of register with each other and one of the members being resilient, means for moving said members to release the arm, and means for moving the closed armature said means being yielding.

22. In a telephone exchange having a series of circuits leading from subscribers' stations, a series of selectors, one for each station, a second series of selectors and a series of connectors, a plurality of circuits for interconnecting said selectors and connectors, each circuit including an electro-magnet, the armature of one of which is normally closed and the other ones are open, a switching mechanism in each selector and connector for controlling said circuits, yielding means for releasing said switching mechanism, and positive means for restoring it to its normal position.

23. In a telephone exchange having a series of circuits leading from subscribers' stations, a series of selectors, one for each station, a second series of selectors and a series of connectors, a plurality of circuits for interconnecting said selectors and connectors, each of which is provided with an electro-magnet and releasing mechanism, one of said magnets being provided with

means for controlling the releasing mechanism, an auxiliary switch in each selector and connector, means for releasing said switch from its normal position, and mechanism connected with the armature of the release magnet for restoring said switch to its normal position.

24. In a telephone exchange having a series of circuits leading from subscribers' stations, a series of selectors, one for each station, a second series of selectors and a series of connectors, a plurality of circuits for interconnecting said selectors and connectors, each of which is provided with an electro-magnet and releasing mechanism, one of said magnets being provided with means for controlling said releasing mechanism, an auxiliary switch in each selector and connector for controlling said circuits, means for releasing the switch from its normal position, and a lock spring connected with the release magnet for restoring the switch to its normal position.

25. In a telephone exchange having a series of circuits leading from subscribers' stations, a series of selectors, one for each station, a second series of selectors and a series of connectors, a plurality of circuits for interconnecting said selectors and connectors, each of which is provided with an electro-magnet and releasing mechanism, one of said magnets being provided with means for controlling said releasing mechanism, an auxiliary switch and a double detent in each selector and connector, a bifurcated rod between the switch and the detent, a perforated lock spring from the armature of the release magnet to the detent and adapted to be placed in engagement therewith, and means for controlling said engagement.

26. In a telephone exchange, an auxiliary switch, an arm thereon, shouldered members for holding the arm in one position, the shoulders of said arms being out of register, and means for moving the members so as to cause the arm to alternately engage with the shoulders and finally be released therefrom.

27. In a telephone exchange, an auxiliary switch, an arm thereon, two shouldered members for engaging with said arm, one of said members being flexible and having its shoulder out of register with the other shoulder, means for moving the switch to cause its arm to engage with the shoulder of the yielding member, and means for moving the members to permit the arm to be successively released from said shoulders.

28. In a telephone exchange, an auxiliary switch, an arm thereon, an electro-magnet, two shouldered members connected with the armature of the magnet, one of which is yielding, means for moving the arm of the switch into engagement with the shoulder of the yielding member, and means for mov-

ing said members to permit the arm to be successively released from said shoulders.

29. In a telephone exchange, an auxiliary switch, an arm thereon, a lock for the arm, an electro-magnet for partially operating 70 the lock, and resilient arms for completing said operation, said arms forming the terminals of an electric circuit.

30. In a telephone exchange, an auxiliary switch, an arm thereon, a lock for said arm comprising two shouldered members, one of which is flexible and has its shoulder nearer its fixed end than the other, an electro-magnet, the armature of which supports said members, resilient arms which form the terminals of a circuit which controls the movement of said armature in its open position, and means on one of said shouldered members for automatically closing said terminals when said magnet is energized. 85

31. In a telephone exchange, a main switch and an auxiliary switch, an arm on the auxiliary switch, an electro-magnet for each switch, the armature of each of which is provided with a projection, 90 the projection on the auxiliary switch magnet forming a lock for its switch and the projection on the other magnet being adapted to engage with the armature of the auxiliary switch magnet and thereby partially 95 control the movements of the auxiliary switch.

32. In a telephone exchange, selectors and connectors, each arranged in series and each instrument provided with a main switch and an auxiliary switch, means for operating the main switch, an electro-magnet for the auxiliary switch, the armature of the auxiliary switch being normally open in the 100 selectors and normally closed in the connectors, positive means for closing each of the selector switches, and yielding means for operating the auxiliary switches.

33. In a telephone exchange, selectors and connectors, each arranged in series, and each instrument provided with a plurality of series of insulated contact points, a switch for each series of points, the switch for the connectors being spring pressed and pivoted and provided with an arm, an electro-magnet for operating each switch, an electro-magnet, the armature of which is provided with a lock for engaging with said arm, and means connected with the armature of the main switch for moving said 110 switch arm into engagement with said lock. 115

34. A switching device for automatic telephone exchanges, comprising selecting mechanism consisting of a plurality of circular rows of contacts arranged one above the other, a longitudinally movable rotary shaft provided with a pair of spring arms adapted to engage said rows of contacts, electro-magnets and mechanism for imparting longitudinal and rotary step-by-step move- 125 130

ments to said rotary shaft, and connecting mechanism comprising a pair of swinging arms and contacts whereby said arms are connected with the arms on said rotary shaft, means tending to swing said arms to effect such connection, and locking means holding said switch arms against movement and releasing the same on the operation of the selecting mechanism.

35. A switching device for automatic telephone exchanges, comprising selecting mechanism containing an electromagnet, connecting mechanism consisting of a switch having an arm, controlling mechanism involving an electromagnet whose armature is provided with a pair of shouldered arms for engaging said arm of the connecting switch, the armature of the selecting magnet being provided with means for actuating the armature of the controlling magnet, and the armature of the latter being combined with means for closing the circuit through the selecting magnet.

36. A switching device for automatic telephone exchanges, comprising selecting mechanism, connecting mechanism comprising a switch arm 31 provided with contact strips, an arm 44 connected with said arm 31, a magnet 8 forming a part of the selecting mechanism, a private magnet 48 having its armature 47 provided with arms 46 and 50 having shoulders 45 and 49 respectively, an arm 60 on the armature of the selecting magnet 8, said arm 60 being arranged to actuate the armature 47 of the magnet 48, and contacts 62 and 63 arranged to be actuated by the armature 47, the shoulders 45 and 49 on the arms 46 and 50 being adapted to engage the arm 44 of the connecting switch.

37. In a switching device for automatic telephone exchanges, the combination of a switch arm 31 supported on a post 32, a spring 38 tending to actuate the arm 31, contact strips carried by the arm 31 and insulated from one another, two sets of contacts with which said contact strips are adapted to make connection, and a double locking arrangement for holding the switch arm 31 normally against operation, said arm being released only on the operation of both of the locking mechanisms thereof.

38. In a switching device for automatic telephone exchanges, the combination of a switch arm 31 supported on a post 32, a spring 38 tending to actuate the arm 31, contact strips carried by the arm 31 and insulated from one another, two sets of contacts with which said contact strips are adapted to make connection, an arm 44 connected with the arm 31, a private magnet 48 having its armature 47 provided with arms 46 and 50 having shoulders 45 and 49 respectively, both of said shoulders being adapted to engage an arm 44, a selecting

magnet 8 having its armature provided with an arm 60 adapted to actuate the armature 47 of the magnet 48, and contacts 62 and 63 combined with means for closing the same when the armature 47 is actuated.

39. A switching device for automatic telephone exchanges, comprising a selecting mechanism embodying a longitudinally movable rotary shaft carrying a pair of contact arms, electromagnets combined with mechanism for imparting longitudinal and rotary movement to said shaft, a connecting switch, a private magnet combined with contacts for controlling the circuit of the rotary magnet of the selecting mechanism, and also combined with means for controlling said switch, and two sets of contacts for the two contact arms, carried by said shaft.

40. A switching device for automatic telephone exchanges, comprising a selecting mechanism embodying a longitudinally movable rotary shaft, carrying selecting and private contact arms, vertical and rotary magnets combined with mechanism for imparting rotary and vertical step-by-step movements to said shaft, a side switch comprising a spring-actuated switch arm provided with a plurality of contact arms, two sets of contacts to co-operate with the arms of said switch, a private magnet, contacts included in the circuit of the rotary magnet of the selecting mechanism controlled by said private magnet, locking devices for holding said switch arm normally against operation and also controlled by said private magnet, and two sets of correspondingly arranged contacts, one for the selecting arm and the other for the private arm on said rotary shaft.

41. A switching device for automatic telephone exchanges, comprising selecting mechanism embodying a longitudinally movable rotary shaft, vertical and rotary magnets combined with mechanism for imparting vertical and rotary step-by-step movements to said shaft, a controlling magnet, relays controlling local circuits including said rotary and vertical magnets, and an auxiliary switch controlling the local circuits, the controlling magnet circuit and the relay circuits.

42. A switching device for automatic telephone exchanges, comprising selecting mechanism embodying a longitudinally movable rotary shaft, vertical and rotary magnets combined with mechanism for imparting step-by-step rotary and vertical movements to said shaft, local circuits including said magnets, relays controlling said local circuits, a controlling magnet, and a switch having a plurality of contact arms combined with contacts for controlling said local circuits, the relay circuits and the circuit of said controlling magnet.

43. A switching device for automatic tele-

- phone exchanges, comprising selecting mechanism embodying a longitudinally movable rotary shaft, vertical and rotary magnets combined with mechanism for imparting 5 step-by-step rotary and vertical movements to said shaft, local circuits including said magnets, relays controlling said local circuits, a controlling magnet, a switch having a plurality of contact arms combined with 10 contacts for controlling said local circuits, the relay circuits and the circuit of said controlling magnet, and two sets of contacts, one for the selecting mechanism and the other for said controlling magnet.
- 15 44. A switching device for automatic telephone exchanges, comprising selecting mechanism embodying a longitudinally movable rotary shaft, vertical and rotary magnets combined with mechanism for imparting 20 step-by-step rotary and vertical movements to said shaft, local circuits including said magnets, relays controlling said local circuits, a controlling magnet, a switch having a plurality of contact arms combined 25 with contacts for controlling said local circuits, the relay circuits and the circuit of said controlling magnet, spring means tending normally to actuate said switch, and locking mechanism for holding the same normally against operation, said locking mechanism being controlled by said controlling magnet.
- 30 45. A switching device for automatic telephone exchanges, comprising selecting mechanism embodying a longitudinally movable rotary shaft, vertical and rotary magnets combined with mechanism for imparting step-by-step rotary and vertical movements to said shaft, local circuits including said 35 magnets, relays controlling said local circuits, a controlling magnet, a switch having a plurality of contact arms combined with contacts for controlling said local circuits, the relay circuits and the circuit of said 40 controlling magnet, spring means tending normally to actuate said switch, locking mechanism for holding the same normally against operation, said locking mechanism being controlled by said controlling magnet, and contacts also controlled by said controlling magnet included in the circuit of the rotary magnet of the selecting mechanism.
- 45 46. A switching device for automatic telephone exchanges, comprising selecting mechanism embodying a longitudinally movable rotary shaft, vertical and rotary magnets combined with mechanism for imparting step-by-step rotary and vertical movements to said shaft, local circuits including said 50 magnets, relays controlling said local circuits, a controlling magnet, a switch having a plurality of contact arms combined with contacts for controlling said local circuits, the relay circuits and the circuit of said 55 controlling magnet, spring means tending nor-

60 mally to actuate said switch, locking mechanism for holding the same normally against operation, said locking mechanism being controlled by said controlling magnet, contacts also controlled by said controlling magnet 70 included in the circuit of the rotary magnet of the selecting mechanism, and two sets or banks of contacts with co-operating contact arms, one set or bank for the selecting mechanism and the other for said controlling magnet 75

47. The combination with a plurality of lines, of a pair of switching devices, each provided with selecting mechanism for said lines, said selecting mechanism embodying 80 an electromagnetic motor device, a local circuit extended between said switching devices, the latter being provided with means operating with the selecting mechanism thereof for connecting with said local circuit, electromagnets at said switching devices, one for each device, said magnets being included in said local circuit, and means whereby each magnet controls the operation 85 of the motor device of the switching device 90 at which it is located.

48. The combination with a plurality of lines, of a pair of switching devices, each provided with selecting mechanism for said lines, said selecting mechanism embodying 95 an electromagnetic motor device, a local circuit extended between said switching devices, the latter being provided with means for connecting with said local circuit, which means are actuated in conjunction with the selecting mechanism, an electromagnet at each switching device in said local circuit, contacts included in the circuits of said motor devices, controlled by said electromagnets, and make and break mechanism also 100 included in the circuit of said motor device.

49. The combination with a plurality of lines, of a pair of switching devices provided with selecting mechanism for said lines, said mechanism comprising a rotary 110 and longitudinally movable shaft provided with selecting fingers, and rotary and vertical electromagnets combined with mechanism for imparting step-by-step rotary and vertical movements to said shaft, a local circuit extended between said switching devices, the latter being provided with connecting arms carried by said rotary shaft, and contacts for said arms, a local circuit 115 extended between said switching devices and provided with electromagnets, one for each switching device, a local circuit including one of the motor magnets of each switching device, contacts in said circuit, controlled by said controlling electromagnet of each 120 switch, and a make and break device for opening and closing the local circuit containing said motor magnet.

50. The combination with a plurality of lines, of a group of switching devices, each 130

switching device comprising two corresponding banks of contacts, one of which is connected with said lines, a longitudinally movable rotary shaft provided with contact arms 5 for each bank of contacts, motor magnets for imparting longitudinal and rotary step-by-step movements to said shaft, a group of local circuits connected with the second bank of contacts of said switching devices and 10 extending between the same, a controlling magnet at each switching device, said magnet being adapted for inclusion in any one of said local circuits, a circuit local to each switching device including one of the motor 15 magnets thereof, contacts in said circuit, controlled by said controlling magnet of each switching device, and a make and break device for making and breaking said last mentioned local circuits.

20 51. The combination with a plurality of lines, of a pair of switching devices each provided with independent selecting and connecting mechanisms, the selecting mechanism embodying an electromagnetic motor device 25 and the connecting mechanism embodying a switch tending normally to operate, a controlling magnet at each switching device for controlling the circuit of said motor magnet and for locking and unlocking said switch, 30 a local circuit extended between said switching devices and including the controlling magnets thereof, the switches of said device being adapted to close the local circuit upon operation to connect with a selected line, and 35 local means for actuating said motor devices of the switching devices.

52. The combination with a plurality of lines, of a group of switching devices each comprising two banks of contacts, one of 40 which is connected with said lines, a longitudinally movable rotary shaft, together with mechanism for imparting step-by-step longitudinal and rotary movements thereto, contact arms on said rotary shaft for the two 45 banks of contacts, a spring actuated switch for connecting with a selected line, a controlling or private magnet combined with mechanism for controlling the circuit of one of the motor magnets of the selecting mechanism, and also combined with means for 50 releasing said spring-actuated switch, a group of local circuits extending between the switching devices and connected with the other bank of contacts thereof, said controlling magnets being adapted for inclusion in 55 said local circuits and the latter being closed by said connecting switches on the operation thereof to connect a selected line, and a make and break device for opening and closing the 60 circuit of the motor device controlled by said private magnet.

53. The combination of three groups of selecting devices and interconnecting lines therefor, electromagnetic operating means 65 for each of the devices, switching mecha-

nism for each device of the first group for disabling its operating means and completing connection to a device of the second group, and switching mechanism for each device of the second group for disabling its 70 operating means and completing connection with a device of the third group.

54. The combination of three classes of selecting devices, interconnecting trunk lines between the first and second classes, operating mechanism for the devices of the first class to select and connect with an idle one of said trunk lines, interconnecting trunk lines between the second and third classes, and operating mechanism for the devices of 80 the second class to select and connect with an idle one of said last trunk lines.

55. The combination with a series of subscribers' lines, of a group of first selectors, one for each subscriber's line, a group of 85 second selectors with interconnecting trunk lines between the same and the first selectors, and a group of connectors with interconnecting trunk lines between the same and the second selectors, said first and second 90 selectors being provided with locking mechanism to maintain the connection to the next group or groups of selecting devices and being also provided with independent selecting and connecting mechanisms, and means 95 for controlling the same, whereby busy trunks are passed and the first nonbusy trunk selected and connected with, the subscribers' lines being connected for selection 100 with said connectors.

56. In a telephone exchange system, a group of lines, switches, multiple terminals of said lines at said switches, multiple test contacts of said lines at said switches, pairs of talking conductors respectively terminating in brushes at said switches, a circuit controlling device at each switch, means for moving said switches over the terminals of the lines of said group, and electromagnetic means at each switch for association with said test contacts for operating a circuit controlling device to maintain open the talking conductors terminating in a switch which is in engagement with the contacts of a line held by another switch.

57. In a telephone system, the combination with automatic connector switches each having line and test brushes, telephone lines, line and test terminals for said lines arranged to be traversed by the brushes of said switches, respectively, selector switches having movable brushes, trunk lines each being connected with the line brushes of a different connector switch, selector switches, multiple terminals of said trunk lines at said selector switches, means for causing a selector switch automatically to move its brushes over the terminals of trunks representing connectors which are busy and to select and isolate the trunk terminals representing a 125 130

connector which is free, test magnets, one for each connector, means for causing the operation of the test magnet of a connector dependent upon the engaged or unengaged condition of the terminals of a telephone line with whose terminals the brushes of said connector are in engagement, and a contact device controlled by said test magnet governing the continuity of the circuit from said line brushes back to the selector, whereby interference with a connection established to said line is prevented.

58. In a telephone system, the combination with automatic connector switches each having line and test brushes and line and test terminals for the lines represented thereon, selector switches having movable brushes, trunks connected with the line brushes of different connector switches, terminals of 15 said trunks at said selector switches, means for causing a selector switch to automatically move its brushes over the terminals of trunks representing connectors which are busy and to select and isolate the trunk terminals representing a connector which is free, test magnets, one for each connector, means for causing the operation of the test magnet of a connector dependent upon the engaged or unengaged condition of the multiple terminals of a telephone line with 20 whose terminals the line brushes of said connector are in engagement, and a contact device controlling the continuity of the circuit from said line brushes back to the selector, said contact device being controlled by said test magnet.

59. In an automatic telephone system, a telephone line consisting of a pair of talking conductors, a source of current, a relay 40 connected between one conductor of said line and said source, a return conductor for said source of current, a pair of selecting contacts, a plurality of groups of waiting contacts adapted to be engaged by said selecting contacts, a magnet controlled by said relay adapted to move said selecting contacts in the selection of a group of waiting contacts, a switch for breaking the circuit of said magnet, a second relay connected between the other conductor of said line and 45 said source of current, and means controlled by said second relay for operating said switch to prevent the further control of said magnet by said first relay, substantially as described.

60. In a telephone system, a telephone line consisting of a pair of talking conductors, a selector for said line, selecting contacts for said switch, a group of waiting contacts 50 adapted to be selected by said selecting contacts, a relay in circuit with the talking conductors of said line, and a source of current for operating said relay, a magnet adapted to cause said selecting contacts to pick out individual waiting contacts in said group,

a source of periodically recurring current, a switch for closing said periodically recurring current through said magnet, and means controlled by said relay for operating said switch, substantially as described. 70

61. In an automatic telephone system, a telephone line consisting of a pair of talking conductors, a selector therefor, selecting contacts in said selector, a plurality of groups of waiting contacts with which said selecting contacts are adapted to engage, a pair of controlling magnets in circuit with the talking conductors of said line through said selector, means for operating said controlling magnets to respectively move said selecting contacts to pick out a group of said waiting contacts, and thereafter to pick out a contact in said selected group, and a side switch for varying the functions of said pair of magnets, substantially as described. 80

62. In an automatic telephone system, a telephone line consisting of a pair of talking conductors, a third conductor, a substation, a selecting switch for said line at a central office, selecting contacts in said selecting switch, a plurality of groups of waiting contacts with which said selecting contacts are adapted to engage, a pair of magnets in circuit with the talking conductors of said line through said selecting switch, a source of current connected between said magnets and said third conductor, means at the substation for completing the circuit through one of said magnets over one conductor of said line and said third conductor 90 to operate said magnet to cause said selecting contacts to pick out a group of said waiting contacts, means at the substation for closing the circuit of the other of said magnets over the other conductor of said line and said third conductor to cause said selecting contacts to pick out certain ones of said selected group of waiting contacts, and a side switch for varying the functions of said magnets, substantially as described. 95

63. In an automatic telephone system, a group of metallic circuit lines each consisting of a pair of talking conductors centering in a central station, metallic circuit trunk lines each consisting of a pair of talking conductors adapted to connect said lines for conversation, a selecting switch for each subscriber's line and for each trunk line, controlling magnets for each selecting switch adapted to cause said switches to interconnect said lines in pairs through said trunks, said magnets being in circuit with the talking conductors of the line or trunk to which the corresponding selecting switch belongs, means at the subscriber's station for operating said magnets separately to build up a connection between two lines, and simultaneously to destroy said connection, substantially as described. 115

64. In a telephone exchange, a series of 120

line switches each of which is individual to a different telephone line, a plurality of groups of connector switches, means for operating any line switch so as to cause a preliminary selection of any desired group of connector switches, automatic means for then selecting an idle connector switch out of the selected group of connector switches, and means for isolating the line switches of the calling and called lines and the connector switch employed so as to prevent interference with the telephonic connection.

65. An automatic selector switch containing multiple test contacts, a test wiper, and a test relay connected in operation to the test wiper through self-locking means.

66. A telephone system including a directly controlled selector switch provided with groups of terminal contacts, a test relay for said selector switch, a test wiper for said selector switch, and a circuit connection for said relay including contacts of said terminal contacts, said test wiper, a contact controlled by said relay and a winding of said relay for selecting an idle one of said terminal contacts.

67. In a telephone system, a called subscriber's line, a plurality of connectors by which said line is temporarily seized, means for automatically selecting idle connectors, and automatic means operating when a called line is found for producing and transmitting busy signals through all the connectors except the one first seizing the line.

68. In a telephone system, a called subscriber's line, means for making said line busy, a connector for seizing said line, means for automatically selecting idle connectors, means for operating the connector to seize the busy line and for maintaining it in connection therewith, and automatic means operated when a called line is found busy for producing and transmitting a busy signal to the calling subscriber to notify him that the said line is already in use.

69. In a telephone system, a called subscriber's line, means for making said line busy, a connector having vertical and rotary motion for seizing said line, the vertical motion for selecting a group and the rotary motion to find a line in the predetermined group, means for operating the connector to seize the busy line and for maintaining it in connection therewith, and automatic means operated when a called line is found busy for producing and transmitting a busy signal to the calling subscriber to notify him that the said line is already in use.

70. In a switching mechanism, the combination with a plurality of terminals, a branch circuit leading from each terminal, a contact element cooperating with the terminals and mechanism for advancing the element progressively, of a motor magnet for setting the mechanism in actuated posi-

tion which is normally inactive, a circuit controlling the operating of the motor magnet which is completed by the contact element as it successively picks up the branch circuits to effect the energizing of the magnet, means for opening said circuit to render the magnet inoperative and a source of current supply for said circuits.

71. In a telephone system, an automatic switch comprising passive contacts and co-operating active contacts, talking strands extending to certain of said active contacts, means outside of said switch for rendering certain of said passive contacts busy, a magnet and co-operating means for advancing said active contacts, a control relay having contacts under its control, means controlled over a single one of said talking strands to close an energizing circuit for said magnet through said contacts of said relay to cause the advance of said active contacts over said busy passive contacts, and means for operating said relay upon the advance of said active contacts over said busy contacts to a position having idle passive contacts to cause the interruption of said magnet circuit.

72. In a telephone system, an automatic switch comprising passive contacts and co-operating active contacts, talking strands extending to certain of said active contacts, means outside of said switch for rendering certain of said passive contacts busy, a magnet and co-operating means for advancing said active contacts, a control relay having contacts under its control, means controlled over a single one of said talking strands to close an energizing circuit for said magnet through said contacts of said relay to cause the advance of said active contacts over said busy passive contacts, means for operating said relay upon the advance of said active contacts over said busy contacts to a position having idle passive contacts to cause the interruption of said magnet circuit, and means controlled by said relay to control the continuity of said talking strands.

73. In a telephone system, an automatic switch comprising passive contacts and co-operating active contacts, talking strands extending to certain of said active contacts, means outside of said switch for rendering certain of said passive contacts busy, a magnet and co-operating means for advancing said active contacts, a control relay having contacts under its control, means controlled over a single one of said talking strands to close an energizing circuit for said magnet through said contacts of said relay to cause the advance of said active contacts over said busy passive contacts, means for maintaining an energizing circuit for said magnet through contacts of said relay until said active contacts are advanced over said busy passive contacts to a position having idle passive contacts, and means responsive to

such advance to operate said relay to cause the deenergization of said magnet.

74. In a telephone system, an automatic switch comprising passive contacts and co-operating active contacts, talking strands extending to certain of said active contacts, means outside of said switch for rendering certain of said passive contacts busy, a magnet and co-operating means for advancing 10 said active contacts, a control relay having contacts under its control, means controlled over a single one of said talking strands to close an energizing circuit for said magnet through said contacts of said relay to cause the advance of said active contacts over said busy 15 passive contacts, means for maintaining an energizing circuit for said magnet through contacts of said relay until said active contacts are advanced over said busy 20 passive contacts to a position having idle passive contacts, means responsive to such advance to operate said relay to cause the deenergization of said magnet, and means controlled by said relay to control the continuity of said talking strands.

75. In a telephone system, an automatic switch comprising passive contacts and co-operating active contacts, means outside of said switch for rendering certain of said passive contacts busy, a magnet and co-operating means for advancing said active contacts, a control relay having contacts under its control, talking strands including said contacts of said relay, means controlled over a talking strand to close an energizing circuit for said magnet through contacts of said relay to cause the advance of said active contacts over said busy passive contacts, and means for operating said relay upon the advance of said active contacts over said busy passive contacts to a position having idle passive contacts.

76. In a telephone system, an automatic switch comprising passive contacts and co-operating active contacts, means outside of said switch for rendering certain of said passive contacts busy, a magnet and co-operating means for advancing said active contacts, a control relay having contacts under its control, talking strands including said contacts of said relay, means controlled over a talking strand to close an energizing circuit for said magnet through contacts of said relay to cause the advance of said active contacts over busy passive contacts, means for maintaining an energizing circuit for said magnet through contacts of said relay until said active contacts are advanced over said busy passive contacts to a position having idle passive contacts, and means responsive to the advance of the active contacts to said idle position to cause the operation of said relay.

77. In a telephone system, an automatic

switch comprising passive contacts and co-operating active contacts, talking strands extending to certain of said active contacts, other switch passive contacts multiply connected to said passive contacts, means associated with said other passive contacts for rendering certain of said first-mentioned passive contacts busy, a magnet and co-operating means for advancing said active contact, means controlled over a talking circuit to close an energizing circuit for said magnet, relay-contacts, a relay having control of said relay-contacts, means operative upon an advance of said contact over said busy passive contacts to close a maintaining circuit for said magnet through certain of said relay-contacts, a busy connection for said active contact including certain of said relay-contacts, and means including said relay responsive to the advance of said active contact over said busy passive contacts to an idle position to actuate said relay-contacts to prevent the further advance of the switch and to render the passive contacts multiply connected to the engaged passive contact busy.

78. In a telephone system, an automatic switch comprising passive contacts and co-operating active contacts, talking strands extending to certain of said active contacts, other switch passive contacts multiply connected to said passive contacts, means associated with said other passive contacts for rendering certain of the first-mentioned passive contacts busy, a magnet and co-operating means for advancing said active contact, means controlled over a talking strand to close an energizing circuit for said magnet, a control relay having contacts under its control, means operating upon an advance of said active contacts over said busy passive contacts to close a maintaining circuit for said magnet through said contacts of said relay, a busy connection for said active contact including contacts of said relay, and means responsive to the advance of said active contact over said busy passive contacts to an idle position to operate said relay to prevent the further advance of the switch, and to render the passive contacts multiply connected to the engaged passive contact busy.

79. In a telephone system, an automatic switch comprising passive contacts and co-operating active contacts, talking strands extending to certain of said active contacts, other switch passive contacts multiply connected to said passive contacts, means associated with said other passive contacts for rendering certain of the first-mentioned passive contacts busy, a magnet and co-operating means for advancing said active contacts, means controlled over a talking strand to close an energizing circuit for said mag-

- net, a control relay having contacts under its control, means operative upon an advance of said active contacts over said busy passive contacts to maintain a circuit for said magnet through said contacts of said relay, a busy connection for one of said active contacts extending through contacts of said relay, talking strands including contacts of said relay, and means for operating said relay as soon as said active contacts reach an idle position after engaging busy passive contacts to stop the further advance of the switch and to render the corresponding passive contacts of the other switches busy and the talking strands continuous. 80
80. In a telephone system, an automatic switch comprising passive contacts and co-operating active contacts, talking strands extending to certain of said active contacts, other switch passive contacts multiply connected to said passive contacts, means associated with said other passive contacts for rendering certain of the first-mentioned passive contacts busy, a magnet and co-operating means for advancing said active contact, means controlled over a talking strand to close an energizing circuit for said magnet, a control relay having contacts under its control, means operative upon an advance of said active contact over said busy passive contacts to maintain a circuit for said magnet through said contacts of said relay, a busy connection for said active contact controlled by said relay, and means responsive to the advance of said active contact over said busy passive contacts to an idle position to operate said relay to prevent the further advance of the switch and to render the passive contacts multiply connected to the engaged passive contact busy. 95
81. In a telephone system, an automatic switch comprising passive contacts and co-operating active contacts, talking strands extending to certain of said active contacts, other switch passive contacts multiply connected to said passive contacts, means associated with said other passive contacts for rendering certain of the first-mentioned passive contacts busy, a magnet and co-operating means for advancing said active contacts, means controlled over a talking strand to close an energizing circuit for said magnet, relay-contacts, a relay having control of said relay-contacts, means operative upon an advance of said active contacts over said busy passive contacts to maintain a circuit for said magnet through certain of said relay-contacts, a busy connection for one of said active contacts including certain of said relay-contacts, means responsive to the advance of said active contacts from a busy to an idle position to operate said relay-contacts to prevent the further advance of the switch and to render busy the passive contacts multiply connected to the engaged passive contact, and means controlled by said relay-contacts to control the continuity of said talking strands. 105
82. In a telephone system, an automatic switch comprising passive contacts and co-operating active contacts, talking strands extending to certain of said active contacts, other switch passive contacts multiply connected to said passive contacts, means associated with said other passive contacts for rendering certain of the first-mentioned passive contacts busy, a magnet and co-operating means for advancing said active contacts, means controlled over a talking strand to close an energizing circuit for said magnet, a control relay having contacts under its control, means operative upon an advance of said active contacts over said busy passive contacts to maintain a circuit for said magnet through said contacts of said relay, a busy connection for one of said active contacts controlled by said relay, means responsive to the advance of said active contacts from a busy to an idle position to operate said relay to prevent the further advance of the switch and to render busy the passive contacts multiply connected to the engaged passive contacts, and means controlled by said relay to control the continuity of said talking strands. 110
83. In a telephone system, an automatic switch comprising passive contacts and a co-operating active contact, means outside of said switch for rendering certain of said passive contacts busy, a control relay having contacts under its control, talking strands including said contacts of said relay, means for causing an initial advance of said active contact by closing a circuit over a single one of said talking strands, means for continuing the advance movement of said active contact over busy passive contacts to an idle passive contact, and then stopping it in engagement therewith, and means whereby said relay maintains said talking strands open while said active contact engages busy passive contacts. 115
84. In a telephone system, an automatic switch comprising passive contacts and a co-operating active contact, means outside of said switch for rendering certain of said passive contacts busy, a control relay having contacts under its control, talking strands including said contacts of said relay, means for causing an initial advance of said active contact by closing a circuit over a single one of said talking strands, means for continuing the advance movement of said active contact over busy passive contacts to an idle passive contact and then stopping it in engagement therewith, and means whereby said relay maintains said talking strands open while said active contact engages busy 120
- 125

passive contacts and closes said talking strands as soon as said active contact engages an idle passive contact.

85. In a telephone system, an automatic switch comprising passive contacts and cooperating active contacts, talking strands extending to certain of said active contacts, other switch passive contacts multiply connected to said passive contacts, means associated with said other passive contacts for rendering certain of the first-mentioned passive contacts busy, means controlled over a talking strand for initially advancing said active contact, means for continuing its advance over busy passive contacts until an idle passive contact is encountered and then stopping it in engagement therewith, a control relay having contacts under its control, a busy connection controlled by said contacts, and means for operating said relay after said active contact has passed over busy passive contacts to apply said connection to a selected idle passive contact and its multiples as soon as such idle contact is selected by said active contact.

86. In a telephone system, an automatic switch comprising passive contacts, and a cooperating active contact, other switch passive contacts multiply connected to said passive contacts, means associated with said other passive contacts for rendering certain of the first-mentioned passive contacts busy, a control relay having contacts under its control, a busy connection controlled by said relay contacts, talking strands having their continuity controlled by said relay, means controlled over a single one of said talking strands for initially advancing said active contact, means for continuing its advance over busy passive contacts into engagement with an idle passive contact, means whereby said control relay maintains said talking strands open while said active contact engages busy passive contacts, and means whereby said relay closes said talking strands and applies said busy connection to a selected idle passive contact as soon as said idle contact is engaged by said active contact after passing busy passive contacts.

87. In a telephone system, an automatic switch, comprising passive contacts and a cooperating active contact, other switch passive contacts multiply connected to said passive contacts, means associated with said other passive contacts for rendering certain of the first mentioned passive contacts busy, a control relay having contacts under its control, a busy connection including contacts of said relay, talking strands including contacts of said relay, means controlled over a talking strand for initially advancing said active contact, means for continuing its advance over busy passive contacts into engagement with an idle passive contact,

means whereby said control relay maintains said talking strands open while said active contact engages busy passive contacts, and means whereby said relay closes said talking strands and applies said busy connection 70 to a selected idle passive contact as soon as said idle contact is engaged by said active contact after passing busy passive contacts.

88. In a telephone system, an automatic switch comprising passive contacts arranged in groups and a cooperating active contact, a primary magnet and associated mechanism for advancing said active contact to positions corresponding to said groups, a secondary magnet and associated mechanism 75 for advancing said active contact over passive contacts in said group, means outside of said switch for rendering certain of said passive contacts busy, means for energizing said primary magnet to produce the primary 80 movement of said active contact, a control relay having contacts under its control, means for closing a controlling circuit for said secondary magnet through said contacts of said relay to produce the secondary 85 movement of said active contact, and means for operating said relay so that, upon the engagement of said active contact with an idle passive contact after passing a busy 90 passive contact, said secondary magnet circuit is interrupted.

89. In a telephone system, an automatic switch comprising passive contacts arranged in groups and a cooperating active contact, a primary magnet and associated mechanism 100 for advancing said active contact to positions corresponding to said groups, a secondary magnet and associated mechanism for advancing said active contact over passive contacts in said groups, means outside of said switch for rendering certain of said passive contacts busy, talking strands, a relay having contacts under its control for controlling said primary and secondary 105 magnets and talking strands, and means for operating said relay upon the engagement of said active contact with an idle passive contact after passing a busy passive contact.

90. In a telephone system, an automatic switch comprising passive contacts arranged in groups and a cooperating active contact, a primary magnet and associated mechanism for advancing said active contact to positions corresponding to said groups, a secondary magnet and associated mechanism 115 for advancing said active contact over said passive contacts in said groups, means outside of said switch for rendering certain of said passive contacts busy, talking strands, a busy connection for said active contact, a relay having contacts under its control for controlling said primary and secondary 120 magnets and said talking strands and busy connection, and means for operating said 125 connection, and means for operating said 130

relay upon the engagement of said active contact with an idle passive contact after passing a busy passive contact.

91. In a telephone system, an automatic switch comprising passive contacts arranged in groups and a cooperating active contact, a primary magnet and associated mechanism for advancing said active contact to positions corresponding to said groups, a secondary magnet and associated mechanism for advancing said active contact over passive contacts in said groups, means outside of said switch for rendering certain of said passive contacts busy, talking strands, a relay having contacts under its control for controlling said secondary magnet and talking strands, and means for operating said relay upon the engagement of said active contact with an idle passive contact after passing a busy passive contact.

92. In a telephone system, an automatic switch comprising passive contacts arranged in groups and a cooperating active contact, a primary magnet and associated mechanism for advancing said active contact to positions corresponding to said groups, a secondary magnet and associated mechanism for advancing said active contact over passive contacts in said groups, means outside of said switch for rendering certain of said passive contacts busy, talking strands, a busy connection for said active contact, a relay having contacts under its control for controlling said secondary magnet and said talking strands and busy connection, and means for operating said relay upon the engagement of said active contact with an idle passive contact after passing a busy passive contact.

93. In a telephone system, an automatic switch comprising passive contacts arranged in groups and a cooperating active contact, a primary magnet and associated mechanism for advancing said active contact to positions corresponding to said groups, a secondary magnet and associated mechanism for advancing said active contact over passive contacts in said groups, means outside of said switch for rendering certain of said passive contacts busy, talking strands, a relay having contacts under its control for controlling said primary magnet and talking strands, and means for operating said relay upon the engagement of said active contact with an idle passive contact after passing a busy passive contact.

94. In a telephone system, an automatic switch comprising passive contacts arranged in groups and a cooperating active contact, a primary magnet and associated mechanism for advancing said active contact to positions corresponding to said groups, a secondary magnet and associated mechanism for advancing said active contact over passive contacts in said groups, means outside

of said switch for rendering certain of said passive contacts busy, talking strands, a busy connection for said active contact, a relay having contacts under its control for controlling said primary magnet and said talking strands and busy connection, and means for operating said relay upon the engagement of said active contact with an idle passive contact after passing a busy passive contact.

95. In a telephone system, two subscribers' telephone lines, a selecting switch for one of said telephone lines, waiting connection terminals for the other of said telephone lines, a plurality of trunk lines, a line selecting switch for one of said trunk lines, trunk selecting switches for the other trunk lines, means under the control of said first subscriber's line for causing said selecting switches to successively select and connect said trunk connecting switches serially with said first line, means for causing the line selecting switch of the last selected trunk line to select and connect with the waiting terminals of said second subscriber's line, means for automatically rendering the selecting mechanism of all said trunk selecting switches inoperative after they have performed their selective functions, and means under the control of said line connecting switch for restoring all of said selecting switches to their normal position, substantially as described.

96. In an automatic telephone system, a subscriber's line, a first selector therefor, a metallic circuit trunk line, controlling magnets for said first selector for causing said selector to select and connect with said trunk line, a secondary selecting switch connected with said trunk line, a pair of controlling magnets and a disconnect magnet for said secondary selecting switch, a pair of contacts closed by the simultaneous operation of said pair of magnets to directly close a circuit through the disconnect magnet of said secondary selecting switch, substantially as described.

97. In an automatic telephone exchange, the combination with a line extending from a substation to a central office, of connecting mechanism for said line at the central office, said mechanism comprising a selecting switch, and an electrically actuated two movement controlling switch adapted in one of its two movements to cause the actuation of said selecting switch, and in its other movement to close the circuit from the aforesaid line to said selecting switch, an actuating circuit for said controlling switch, and means at the substation of said line for changing said actuating circuit to effect the operation of said controlling switch.

98. A telephone system including telephone lines having test terminals adapted to be differently connected according to the

- busy or idle condition of the lines, a test wiper for engaging said test terminals, a switch in circuit with said wiper and adapted to establish connections dependent upon the busy or idle condition of the encountered line, an electromagnet sensitive to the busy or idle condition of the tested line for controlling said switch, and a second electromagnet for releasing said switch.
- 10 99. In a telephone system, the combination with a selector, of a relay, of a locking armature controlled by said relay and normally connected with a private terminal or wiper of said selector, and a circuit connection including said relay, said armature and said terminal determining the selection of idle contacts.
100. In a telephone system, subscribers' lines, connector switches having line terminals thereon and brushes for engaging said terminals to establish connections to said lines, selector switches adapted automatically to select an idle connector switch, test relays, one at each connector switch, and means operated by the test relay of each connector switch for controlling the circuit to its line brushes, whereby an effective connection to a busy line is prevented.
101. In a telephone system, subscribers' lines, connector switches having line and
- test brushes, multiple line and test contacts of said lines arranged to be traversed by said brushes, selector switches having brushes, trunk lines, each being associated with the line brushes of a different connector switch, multiple terminals of said trunk lines arranged to be traversed by said selector switch brushes, means for automatically moving the brushes of a selector switch over the terminals of trunk lines associated with connector switches which are busy and for selecting and isolating a trunk line associated with a connector switch which is idle, test relays one individual to each connector switch, means for controlling the condition of the test relay of a connector switch dependent on the engaged or unengaged condition of the multiple terminals of a telephone line with the terminals of which the brushes of said connector switch are in engagement, and devices controlled by said relays for preventing a plurality of connector switches from establishing simultaneous talking connections to the same line.
- In testimony whereof we have signed our names to this specification.

ALEXANDER E. KEITH.
JOHN ERICKSON.
CHARLES J. ERICKSON.
